UNITED STATES PATENT OFFICE.

CHARLES H. PURCELL AND LAURENCE I. HEWES, OF PORTLAND, OREGON.

PAVEMENT FOR ROADS AND STREETS.

1,393,699.

Specification of Letters Patent. Patented Oct. 11, 1921.

Application filed March 1, 1921. Serial No. 448,849.

(FILED UNDER THE ACT OF MARCH 3, 1883, 22 STAT. L., 625.)

To all whom it may concern:

Be it known that we, CHARLES H. PURCELL and LAURENCE I. HEWES, citizens of the United States, and employees of the Department of Agriculture, residing in Portland, in the county of Multnomah and State of Oregon, have invented a new and useful Pavement for Roads and Streets, of which the following is a specification.

10 This application is made under the act of March 3, 1883, chapter 143 (22 Stat., 625), and the invention herein described and claimed may be used by the Government of the United States, its officers and employees, 15 and by any person in the United States without payment to us of any royalty thereon. We hereby dedicate the same to the free use of the Government and the people of the United States.

20 Our invention relates to that type of construction to which slabs are manufactured separately and subsequently deposited on the subgrade adjacent to each other thus forming the pavement. The objects of the 25 invention are: first, to provide a practicable method of constructing a pavement where natural conditions make it difficult and expensive to construct the pavement in place on the subgrade; second, to make it possible

30 to construct a pavement which can be used immediately on completion thus avoiding interference with traffic; third, to provide a method by which the pavement is constructed under the most favorable conditions 35 in a stationary plant, and fourth, to make it possible to build pavement under weather conditions which prevent construction of pavement in place.

We attain these objects by the method 40 illustrated in the accompanying drawings, in which Figure 1 is a top view of portions of three slabs; Fig. 2 a vertical section of same; Fig. 3 an isometric view of edge of panel; Fig. 4 a connection detail and Fig. 5 45 an isometric view of same.

Similar figures refer to similar parts throughout.

The slabs 1 with top reinforcement 2 and bottom reinforcement 3 are precast and then transported to the proper place on the sub-grade 4. A sand cushion 4^a may be used to even up irregularities in the subgrade so as to give a uniform bearing for the slabs. Adjacent slabs are held together by connections consisting of U bars 5 and rods 6 which are driven through openings formed by grooves 7 and through loops 8 formed by U bars 5. The recess 9 serves to allow for the projecting loops of U bar embedded in adjacent slab. The joints 10 between slabs 60 may be filled with material poured in after slabs are in place and rods 6 driven in place. A suitable number of the joints may be filled with bitumen allowing for expansion of the slabs. A cushion 11 consisting of sand and cement may be placed under each expansion joint. After the slabs are well bedded, but before the bitumen is poured, water may be poured on the sand and cement cushion, forming grout.

It is to be understood that we do not limit ourselves to the form of the invention here shown for the purposes of illustration except as we may be limited by the following claims forming a part hereof:

We claim:

1. The combination of a precast slab of paving material and a connection with an adjacent slab, such connection consisting of overlapping U bars and a rod passing 80 through the loops formed by the U bars and grooves in the slabs substantially as described.

2. The combination of a precast slab of paving material and a connection with an adjacent slab, such connection consisting of overlapping U bars, a rod passing through the loops formed by the U bars and grooves in slabs, the space between adjacent slabs being filled with grout or bitumen substantially as described.

CHARLES H. PURCELL.
LAURENCE I. HEWES.
